UNITED STATES PATENT OFFICE

160,258

PUMP

Harry Goodman, Britton, Okla.

Application May 20, 1949, Serial No. 2,781

Term of patent 14 years

(Cl. D65—1)

To all whom it may concern:

Be it known that I, Harry Goodman, a citizen of the United States, residing at Britton, in the county of Oklahoma and State of Oklahoma, have invented a new, original, and ornamental Design for a Pump, of which the following is a specification, reference being had to the accompanying drawings, forming part thereof.

Fig. 1 is a perspective view showing the front, top and one side of a pump embodying my new design.

Fig. 2 is a perspective view showing the front, top and other side thereof;

Fig. 3 is a perspective view showing the front, bottom and side illustrated in Fig. 2; and

Fig. 4 is a perspective view showing the rear, the top, and the side shown in Fig. 1.

I claim:

The ornamental design for a pump, as shown.
HARRY GOODMAN.
